GUN PRIMER MECHANISM

Cutler D. Knowlton, Rockport, Mass., assignor to
 United Shoe Machinery Corporation, Flemington, N. J., a corporation of New Jersey

Application February 4, 1946, Serial No. 645,373

10 Claims. (Cl. 89—27)

1

This invention relates to primer mechanisms of ordnance in which projectiles are separate from the powder charge as distinct from ordnance using fixed ammunition.

With medium or larger size guns using separate loading ammunition, the breech member must be provided with some means of preventing powder gases from passing to the rear into the threads and other accurately made parts of the breech mechanism. The erosive power of such gases is such that a gun would soon be rendered useless if a sealing means were not made effective. However, such sealing means must afford a passage for the flame of the primer to pass through to the powder charge of the gun. The invention is more especially, although not exclusively, intended for use as a primer mechanism to be mounted upon a breechblock carrier, the latter being adapted to support the breechblock in both swinging and rotative motion during opening and closing of the breech. In such an installation, the breechblock is provided with an obturator (of the De Bange type) having an axial vent for the primer flame and the rear portion of the obturator vent necessarily has associated therewith a primer mechanism which is as reliable, convenient and close fitting as possible in operation. In an ordnance installation of this character a considerable force is required to urge a primer shell tightly into the tapered chamber of the supporting plug thus assuring no gas leakage. A considerable force is also required to withdraw or eject a spent primer shell.

It is an object of the present invention to provide an improved primer mechanism attachable to a vented obturator spindle in which mechanism a longitudinal motion of a slidable bolt will positively and firmly enclose a primer in position for firing without gas leakage.

Another object is to provide a primer mechanism and obturator spindle combination for ordnance in which the parts are firmly and permanently locked together despite repeated jarring during use.

Still another object is to provide a primer mechanism in which a primer may conveniently be fired by means of a pull on a movable member for actuating the firing mechanism, the pull on the member being exerted at any angle (up to 90°) with the direction of motion of the movable member.

Another object is to provide a primer mechanism utilizing an axially slidable bolt with a handle for forcing home the primer and with means normally locking an associated firing mechanism, which locking means is automatically released when the slidable bolt is placed in firing position.

Another object is to provide a primer mechanism utilizing a bolt axially slidable in alignment with a primer and obturator vent, and an ejector,

2

the bolt being actuatable as a direct thrust member for forcing home the primer and the ejector being actuatable upon manually withdrawing the bolt.

For the purposes in view, and in accordance with various features of the invention, the illustrated mechanism is shown in assembled association with an obturator spindle as carried by a breechblock carrier of conventional type. A feature of the invention consists of a cam sleeve member attachable to an obturator spindle and carrying primer firing means and a primer rim holder on a bolt axially slidable within the cam sleeve member for pressing the primer home. Another feature is the firm and what may be considered permanent joinder of the obturator spindle with the primer mechanism, the joinder means employing threaded coupling members supporting and maintaining a cylindrical cam sleeve member of the primer mechanism in definite and rigid relation to the spindle. Another feature is a flared aperture on the primer mechanism and a cam knob linked to the firing mechanism which knob is arranged to cooperate with and tilt in the flared aperture in such a manner as to increase the angle from which the primer may be fired. Still another feature is an axially slidable bolt with a handle for forcing home the primer, the bolt carrying primer firing mechanism which is automatically unlocked only when the bolt is in firing position. Another feature is a primer mechanism provided with a sleeve member in which an axially slidable bolt is used for forcing home a primer, the primer mechanism carrying a pivoted trough-like ejector actuatable upon straight-line withdrawal of the bolt from firing position.

The above and other features of the invention, including novel details of construction and combination of parts, will now be more particularly described in connection with the accompanying drawings and pointed out in the claims.

In the drawings,

Fig. 1 is a view partly in plan and partly in section of a primer mechanism embodying the present invention, the primer mechanism being illustrated as installed on a gun with a conventional breechblock obturator and the parts of the primer mechanism being shown in loading position with a primer in line with the obturator vent preparatory to being pushed lengthwise into firing position;

Fig. 2 is an enlarged plan view, partly in section, of a portion of the primer mechanism shown in Fig. 1;

Fig. 3 is a section on the line III—III of Fig. 2;

Fig. 4 is an elevational view of a portion of the mechanism shown in Fig. 2, as taken from the right, with the fixed and outer sleeves removed and a part broken away, the primer shell being shown in dot and dash lines;

Fig. 5 is a view looking in the direction of arrow V in Fig. 3 including the fixed cam sleeve but omitting the outer sliding sleeve;

Fig. 6 is a section and elevation view of the primer mechanism, showing the parts in locked position with the primer properly positioned for firing;

Fig. 7 is a development of a portion of the fixed cam sleeve and is drawn to approximately the same scale as is Fig. 1;

Fig. 8 is a view in end elevation of the mechanism shown in Fig. 6 with the addition of several parts of the breechblock carrier;

Fig. 9 is a section on the line IX-IX of Fig. 6;

Fig. 10 is a view in side elevation of the sliding bolt in Fig. 9, with the position of the operating handle being indicated by a full line in "open" position and by dotted lines when in position for primer ejection, with the sliding or outer sleeve omitted and the fixed cam sleeve shown partially in dash lines;

Fig. 11 is a view similar to Fig. 6 of a portion of the mechanism shown therein, with the hammer and associated parts pulled back and shown in the positions they assume immediately prior to release and firing of the primer;

Fig. 12 is a side view of the lanyard arrangement shown in Figs. 6 and 11;

Fig. 13 is a side elevation of the pull block and sear spring;

Fig. 14 is a section on the line XIV-XIV of Fig. 13;

Fig. 15 is a view smaller to that of Fig. 2 but with the parts as positioned immediately subsequent to ejection of a spent primer; and

Fig. 16 is a section on the line XVI-XVI of Fig. 15.

In medium or large size guns it is well known to use an obturator with a breechblock 10 and a gun tube 11, as shown in Fig. 1, which obturator comprises a steel mushroom head 12 against which the force of the explosion longitudinally of the gun is exerted, a resilient or elastic pad 14, split rings 15, a steel disk 16, and a spindle 18. An obturator of this type is fitted within the breechblock 10 and pressure of the gases against the mushroom head 12, upon firing, compresses the elastic pad 14 and also presses the split rings 15 surrounding the spindle against the walls of the bore and the spindle thus effectually preventing leakage.

As the mechanism of the invention is described herein, the terms "downwardly" and "upwardly" are used merely for convenience, it being assumed that medium or large size guns, for which the invention is particularly adapted, are usually fired at an angle with the vertical. Breechblocks are conventionally mounted to rotate independently of the obturator parts and, because of this, any sticking of an obturator to its seat in the gun tube 11, will not interfere with the rotation of the block 10 when opening the breech. After proper rotation of a breechblock 10 to disengage the usual interrupted threads 19, the block 10 and obturator may be readily withdrawn from the gun tube 11.

An obturator spindle 18 of this type is conventionally provided with a vent 20 passing through its full length, permitting passage of a flame from a primer 22 (Fig. 1, 2 and 6) to the powder charge of the gun. A sleeve 24 (Fig. 1) forms a pintle upon which the breechblock may rotate, and this sleeve 24 forms a part of the breechblock carrier 25 which supports the breechblock for

movement toward and away from the gun. The obturator spindle 18 is keyed at 23 to the sleeve 24, preventing the rotation of the spindle with respect thereto. A helical spring 26 serves to hold the obturator firmly in place within the breechblock 10. The spring is located in a recess in the sleeve 24 and surrounds the rear end of the spindle 18 and bears against a cylindrical coupling member 28 joined to the spindle 18 by means of right-hand threads 21. A second cylindrical coupling member 30 is joined to the coupling member 28 by left-hand threads 32. A fixed or cylindrical cam sleeve 34 (Figs. 1, 2, 6 and 15) is provided with an end flange 36. This sleeve 34 constitutes a part of the primer mechanism generally indicated at 40 in Fig. 1. The two coupling members 28 and 30 are provided with threads of opposite pitch in order that they may be turned tightly against each other and thereby press the sleeve member 34 into rigid and permanent relation against the end of the spindle 18 by means of the flange 36. A thin-walled locking cylinder 29 may surround the coupling member 28 and in order positively to lock the coupling members together the cylinder 29 is provided with fingers 31 and 33 bent into suitable recesses cut into the coupling members. The flange 36 is provided with a tab or key 37 for engaging a keyway in the end of the spindle 18 as well as in the coupling member 28 and this feature prevents relative rotation of the immediately associated parts as will further appear.

The breechblock operating mechanism herein disclosed (Fig. 1) is of conventional form and utilizes a shaft 42 rotatively mounted in the breechblock carrier 25 and provided with a flange 44 notched at one portion 46 of its circumference for engagement with a sliding block 48. In Fig. 1 the block 48 has been moved to the left and out of engagement with the flange 44 in the notch. The flange 44 is integral with the shaft 42 and also with an eccentric member 50 having a crank pin 52 rotatable in a cylindrical member 54 inserted within the breechblock 10. The sliding block 48 carries a pin or stop means 56 (movable in a slot 57 of a plate 59 forming a part of the conventional breechblock carrier 25) and is urged toward the axis of the breechblock by a spring 58. The sliding block 48 is provided with a finger 60 adjacent to the sleeve member 34. It is to be understood that the carrier 25, including the shaft 42, block 48, and cylindrical member 54 are all conventional details of a modern breech mechanism. As will be understood the finger 60 and the block 48 (of which the finger 60 is a part) may be moved to the right, that is, the left end of the block 48 may be positioned within the slot 46 only when the breechblock is properly closed. The arrangement of the parts is such that if the breechblock were not fully closed and in position for firing, the notched portion 46 would not be in alignment with the block 48 and the latter element would strike the flange 44 in the event that finger 60 were urged to the right from its position as shown in Fig. 1.

The primer mechanism 40, constituting the subject matter of the present invention, comprises the cam sleeve 34 above referred to, which sleeve supports the primer mechanism in alignment with the obturator spindle. As shown in Fig. 2 the cam sleeve 34 is in firm and abutting relation with the end of the obturator spindle 18. A cylindrical primer holding block 64 is fitted within an axial chamber 66 of the sleeve member 34 and has a reduced portion 68 (Fig. 2) threaded

into a recessed portion of the spindle to bear against a soft metal or copper washer 70 to form a gas-tight joint immediately surrounding the flame passage or vent 20. The block 64 is provided with a longitudinal passage to coincide with the vent 20 of the spindle and this passage is enlarged as well as tapered at 72 to hold a primer tightly. It is to be noted that the block 64 has flattened portions 74, one of which is shown in Figs. 2 and 15, to facilitate assembly. The rear end portion of the primer block 64 is tapered to provide a conical cam surface 76 which is designed to align with a cam surface 78 forming one side of an opening 80 in the sleeve 34 (Figs. 2 and 5). A longitudinally slidable and rotatable outer sleeve 82 is mounted on the fixed or cam sleeve 34 and is provided with a protuberance 84 as well as an eccentric cam 86, as shown in Fig. 1. The eccentric cam 86 is also shown in Fig. 8. A boss 90 is formed on the side of the outer sleeve 82 and is recessed and threaded at 92 (Fig. 6) to accommodate the exterior shell 94 of a handle generally indicated at 96. The shell 94 has affixed within its open end a disk 98 and a rod 100 an enlarged portion 102 of which is fitted to slide within a reduced portion of the exterior shell 94. The inner end 104 of the rod 100 is arranged to extend through the sleeve member 34 and within a recess 106 of an axially slidable bolt 110 arranged within the sleeve 34. A coiled spring 112 is arranged within the handle 96 to hold the rod 100 to the left as viewed in Fig. 6. A knurled cylindrical member 114 is pinned at 116 to the rod 100 and bears a pin 118 an enlarged portion of which extends freely through an opening in the disk 98.

The sliding bolt 110 is provided with a flange 111 at one end which serves as a closure for the sleeve 82 at all times as the bolt 110 and outer sleeve 82 are arranged to slide together because of the interlocking handle rod 100. At its opposite end the bolt 110 carries a primer rim holder 120. This holder has a U-shaped or dovetail slot 122 (Figs. 3 and 6) into which the rim of the primer 22 may be placed. The holder 120 is held tightly within a central recess in the bolt 110 by means of a nut 124 threaded in the recess and bearing against a shoulder 126 (Fig. 6) of the primer rim holder, the holder being properly positioned within the bolt 110 by a washer 130 bearing on a shoulder 132 of the bolt 110. A primer firing pin 134 is located within a recess 136 of the holder 120 and the end of the firing pin is held flush with the bottom face of the slot 122 of the holder 120 by means of a spring 138 which acts to hold the vented flange 140 of the firing pin 134 against the washer 130. The flange 140 has one or more vents 141 formed therein. The washer 130 has an enlarged opening formed therein for the cylindrical portion 142 of the firing pin. A vent 144 is provided in the wall of the sliding bolt 110 just beneath the washer 130 to prevent the pocketing of any gases. The bolt 110 is provided with a central bore to receive and to permit endwise or axial movement of a hammer 150 which is urged toward the cylindrical portion 142 of the firing pin 134 by two concentric compression springs 152 and 154. The head of the hammer 150 is vented at 155 preventing pocketing of gases.

Formed in the sliding bolt 110 in axial alignment with the handle recess 106 is a radial and cylindrical passage 156 in which is mounted a locking pin 158 having beveled ends. When the sliding bolt 110 is in non-firing position the locking pin 158 engages the hammer 150 in a cylindri-

cal groove 160 formed therein. When the parts are so positioned the interior cylindrical wall surface of the sleeve member 34 holds the pin 158 in locking position thus preventing endwise movement of the firing hammer 150. When the primer mechanism is placed in firing position, however, by means of the handle 96 the pin 158 will be moved into alignment with a passage 164 formed in the fixed sleeve 34 and having its inner 10 end portion tapered to receive the pin 158. In this position it will be evident that the beveled pin 158 is free to move outwardly when a pull is exerted upon the hammer 150. This outward motion is brought about by the slanted side of the groove 160 engaging the beveled inner end of the pin 158. The hammer is therefore easily unlocked and ready for operation. Upon disassembly of the parts, a pin 300 is utilized to retain the small pin 158 in the bolt 110.

20 A longitudinal, rigid member or sleeve 170 surrounds a mid portion and one end of the hammer 150 and this member carries a fixed pin 172 to insure correct assembly therewith of a sear block 174 movable therein (see Figs. 6, 11 and 13). 25 The sear block 174 is mounted in a transversely extending rectangular passage 175 (Fig. 13) within and near the upper end of the longitudinal member 170. The sear member 174 is provided with a bore 177 (Fig. 14) and the hammer with 30 a reduced portion 179 thus permitting limited radial movement of the sear member relative to the hammer 150. The bore 177 is of a diameter slightly in excess of the hammer diameter at lands 181 and 183 which are joined by the reduced 35 portion 179. Land 181 has a flat right angular shoulder 185 for engaging the sear block 174 when the parts are positioned as shown in Fig. 11. An arcuate spring 176 (Fig. 14) is mounted upon the two parts 170 and 174 and tends to hold the two 40 parts out of axial alignment. The circumference of the sear block 174 is provided with conical seats 187 and 191 (Fig. 13) and part 170 has a conical seat 183. At one end of the sliding bolt 110 is mounted a recessed outer block 178 which is 45 threaded at 180 within the recess 182 of the bolt. The block 178 has an inner conical seat 189 and is axially bored at 195 to receive the slidable and longitudinal member 170 as well as a spring 184 mounted to press the longitudinal member 170 inwardly. As may be seen in Fig. 6, the hammer 150 extends within a recess 186 in the sleeve member 170. The sleeve member 170 has a ring 188 integral with one end thereof, and a link member 190 bent in the form of a U passing 50 through the ring, this arrangement serving to hold a cam knob 192 to the member 170 and permitting universal movement. The cam knob 192 has a flat surface 194 arranged to seat on the bottom of the recess 197 within the block 178 55 when the hammer 150 is in the position shown in Fig. 6. The side surface of the cam knob 192 is concaved and proportioned to coact with the flared opening or annular wall of the recess 197 in the block 178 as will further appear. A split pin 196 is used to hold the U-shaped link 190 in locked relation to the cam knob 192 and the cam knob is fitted with an ear 198 to which a lanyard 200 may be fastened.

70 The nature of the fixed or cylindrical cam sleeve 34 may best be understood by a consideration of the developed view as presented in Fig. 7. At one end of the sleeve are located the flange 36 and key 37 (already described) by the use of which the priming mechanism is rigidly affixed to the spindle 18 in rigid relation. In addition to

7
the opening 80 located in the bottom of the sleeve there is an angular opening 202 to accommodate the movement of the inner end 104 of the rod 100 when the parts are assembled. Particular attention is directed to the cam surface 204 at one side of the opening 202. A third opening 206 is formed in the top of the sleeve 34 through which primer cartridges may be individually charged and ejected. A U-shaped groove 208 is formed in the rear end of the sleeve 34 with the open end of the groove extending to the angular slot 202. This groove holds a U-spring member 210 having one leg thereof 212 (Fig. 10) of such length as to extend into the slot 202 for a purpose to be described.

The sliding bolt 110, as heretofore stated, is drilled at 106 to accommodate the end 104 of the rod 100 and integral with the bolt 110 is a projection 214 (Figs. 9 and 10) having a semi-circular recess 216 in alinement with the recess 106. The fixed sleeve 34, as seen in Fig. 9 and also in Fig. 7, has a shoulder 220 at one side of the opening 202, this shoulder 220 constituting a stop to limit rotation of the sliding bolt 110 as it is moved to firing position. The other end of the slot 202 constitutes a stop surface 222 (Fig. 7) for the bolt 110 when it is rotated to open position—that is, for the ejection of a spent primer and insertion of a new one.

The outer sleeve or shield 82 is provided with an integral cylindrical portion 230 (Figs. 1, 2 and 15) in which is mounted a bolt 232 having a flanged head 234 drilled at 236 to receive one end of a coiled spring 238 surrounding the bolt 232. The spring 238 is placed under a slight compression and is also unwound slightly, causing the end 240 to bear against a shoulder 242 of a flanged collar 246 pinned at 248 to the sleeve 82, preventing relative movement. The rod 232 has one end 250 that is slightly reduced in diameter to receive the arm 252 of a trough-like ejector member 254. The reduced portion 250 is threaded for the reception of a nut 256. One end of the intermediate portion of the rod 232 is flattened, as shown at 258, resulting in a shoulder 260 (Fig. 15) at opposite sides of the rod 232. The arm 252 is recessed at 262, this recess being of such width as closely to fit the flattened portion of the rod 232. With this construction the arm 252 is rigidly affixed to the rod 232 by being pressed against the shoulders 260 when the nut 256 is tightened. Attention is directed to the fact that the rod 232 is of such length and the other parts are so proportioned that a slight clearance exists between the flange 234 and the end of the cylindrical portion 230 when the primer mechanism is open as in Fig. 2. One end of the arm 252 is provided with a finger piece 270 by means of which the arm 252 may be rotated manually. The piece 270 may serve as a stop for limiting the outward swing of the arm 252 and it also may aid in the assembly or disassembly of the parts, it then being desirable to hold arm 252 out of the way.

The trough in the ejector arm 252 is slotted at 280 to facilitate cleaning. At one side of the ejector arm and integral therewith is a cam member 282 having two cam surfaces 284 and 286 which intersect, as shown in Fig. 4. One end or side of the ejector arm 252 is curved upwardly and rearwardly to form a cam surface 290. The rear face of the arm 252 bears a curved shoulder 292 (Fig. 4) formed to engage the exposed bottom surface of the primer rim holder 120 when the primer trough is in a position of alinement with the obturator vent 20 and the passage in the

5 block 64 (Fig. 3). This shoulder 292 is of a width which is slightly less than that of the maximum clearance between the head 234 of the bolt 232 and the end of the spring casing or cylindrical portion 230.

On the interior wall of the fixed sleeve 34 and in position to be contacted by the cam member 282 are two cam surfaces 294 and 296 (Figs. 3 and 5).

Assuming that the breechblock 10 is fully closed, a gunner may place a primer through the opening 206 of the fixed sleeve 34 and within the trough of the ejector with the primer rim within the rim holder 120. The trough, being in its uppermost position, as shown in Fig. 16, may be pushed down until the shoulder 292 slips under the rim holder 120 because of the action of cam 282 (Fig. 5) when its lower surface 286 slides down fixed cam surface 294. During such cam action the trough and arm 290 move forwardly with relation to the rim holder 120 and the outer sleeve 82 because of the yielding action of the coil spring 238 which uncoils slightly and compresses axially until the shoulder of flanged head 234 is stopped by the cylindrical spring enclosing portion 230. A further downward motion of the trough arm 290 moves the outer sleeve 82 and the sliding bolt 110 (movable together because of end 104 of handle rod 100) rearwardly to deflect the spring end 212 rearwardly and away from the forward wall of the fixed groove 208 in which the spring 210 is retained (Fig. 15). When the shoulder 292 has swung down and into position to slip beneath the rim holder 120, spring end 212 urges rod end 104 forwardly carrying the outer sleeve 82 and sliding bolt 110 with it. The compression of coil spring 238 is simultaneously released and the shoulder 292 of the ejector trough is latched beneath the primer rim holder 120 in the position shown in Figs. 2 and 3. It is to be understood that during the above referred to latching operation of the primer trough the handle 96 will lie in a plane inclined at a slight angle to the horizontal end including the line marked "Open" in Fig. 8.

In order to ram the primer 22 home, that is, within the chamber 72, the gunner first pushes the handle 96 forwardly (toward the gun tube 11) until rod end 104 strikes the cam surface 204 of the fixed sleeve angular slot 202. As heretofore stated, the outer sleeve 84 and the sliding bolt 110 will move axially with relation to the fixed sleeve 34. The longitudinal leg of angular slot 202 is of sufficient length to permit the required forward motion of bolt 110. During this movement the ejector arm 252 is swung downwardly and out of the way by its cam surface 290 striking the cam surfaces 76 and 78, the arm 252 assuming the position shown in dotted lines in Fig. 3. This motion stores potential energy in spring 238 for subsequent spent primer ejection. As the handle 96 swings downwardly (the forward movement is changed to a subsequent downward movement by the contact of rod end 104 with the cam surface 204), the primer is given a twist or slight rotation. It is pushed home by a continued forward and downward push exerted on the handle until the latter reaches its extreme forward position which is the stop or locked position as shown in Figs. 6, 8 and 9. The fixed sleeve is of relatively heavy construction and the annular leg of the angular slot 202 is of such width as snugly to receive the rod end 104 and hold the bolt 110 in its firing or battery position, as shown in Figs. 6, 9 and 11. If the breechblock is not properly closed, the gunner will be unable to push the handle the full forward

distance as the protuberance 84 will strike the finger 60 and the block 48 will strike flange 44. If the breechblock is properly closed, the block 48 will slide within the notch 46 as protuberance 84 pushes the finger 60 to the right. The eccentric cam 86 serves to retain the block 48 in the notch 46 while the primer mechanism is being turned and placed in firing position.

The primer is now ready for firing. Any angular and outward pull on the lanyard 208 will cause the cam knob 192 to tilt on the flared mouth of the member 178. This will result in a longitudinal outward pull on the member 170 as well as on the hammer 150. The square shoulder 185 of the hammer will be contacted by the sear block 174 thus causing the pull on the hammer and also the compression of springs 152, 154 of the hammer and spring 184 about member 170. The sear block 174 will first be urged toward a central position by its conical surface 187 engaging the conical seat 189 on member 178 and a portion of the block 174 will enter the bore 195. A further pull on the lanyard will cause conical surface 191 to engage the conical seat 189 and thereby place bore 186 and bore 177 in alinement. This relation of the parts will terminate engagement of the shoulder 185 with the edge of the sear block, and the hammer 150 will be released to strike the cylindrical portion 142 of the firing pin 134. The surfaces 191 and 193 are so related in position that the hammer will be released slightly before surface 193 comes to a positive stop on the conical seat 189.

The primer being fired, the handle 96 is swung upwardly and then rearwardly. Cam surface 204 on sleeve 34 aids in initially jarring the spent primer loose and also initiates its withdrawal rearwardly. A continued pull on the handle 96 rearwardly will permit spring 238 to swing the ejector arm 252 upwardly and a further continuation of the rearward pull on the handle 96 will result in the moving cam surface 286 (Fig. 5) striking the fixed cam surface 294. The striking together of these two surfaces has two effects. It gives an added impetus to the upward swing of the ejector trough, sending the trough to its uppermost position as shown in Fig. 16 thus ejecting the spent primer forcibly. Its other effect is to retard slightly the rearward motion of the ejector arm 252 and rod 232 with respect to the rearwardly sliding bolt 110 and primer rim holder 120—i. e.—spring 238 will yield slightly until the head 234 of bolt 232 contacts the portion 239 of shield 82 (Fig. 15) and spring end 212 (Fig. 10) will yield slightly (as permitted by the width of its groove 208) thereby causing the primer rim holder 120 to travel rearwardly a short distance beyond the shoulder 292 of the ejector arm (Fig. 15). In the event that the ejector arm does not swing upwardly in the proper manner, the moving cam member 282 will be too low as the handle 96 is pulled back. As a consequence moving cam surface 284 will strike fixed cam surface 296 and swing the ejector arm down again. This feature prevents possible breakage of the parts. Premature ejection of a spent primer (before the primer 22 has cleared the block 64) is precluded as the engagement of cam surfaces 290 and 78 prevents the arm 252 from rising until the proper time. The cam member 282 and also the coating cam surfaces 294 and 296 are not essential for proper operation of the primer mechanism but their provision is preferred in order that ejection be made positive. It should be understood, however, that ejection by spring action alone may satisfactorily be carried out. The gunner is

enabled by the present mechanism to reciprocate the handle 96 until ejection is carried out. After ejection the momentary deflection of spring end 212 partially disappears and the sliding bolt 110 as well as the primer rim holder 120 are simultaneously pushed forwardly and the latter engages or abuts the ejector arm 252 below the shoulder 292 as shown in Figs. 15 and 16. The deflection remaining of the spring end 212 furnishes sufficient force to maintain the ejector trough and rim holder 120 in contact as in Figs. 15 and 16. The mechanism is then in readiness for latching of the primer trough and the insertion of a fresh primer as set forth above.

The only change which preferably should be made to the conventional obturator spindle in contemplation of the use of the present primer mechanism is the cutting of a keyway therein to receive the tab 37 of the sleeve member 34.

In assembling the primer mechanism 40 on the obturator spindle 18, the coupling member 28 is first screwed on by hand, the right-hand threads 21 conventionally being made with a substantial amount of clearance or looseness. When the keyway cut in the member 28 is properly alined with the keyway in the spindle 18, the primer mechanism is placed in position with the tab 37 preventing any relative rotation of the member 28 in excess of the clearance at the sides of tab 37. However, all relative rotation should be eliminated in order to secure a firm and permanent joinder of the parts despite repeated and violent jarring due to firing of the gun or extreme violence in the use of the handle 96. With this purpose in mind, coupling member 30 was provided with threads to the opposite hand (left-hand threads) and when member 30 is turned to the left and tightened, member 28 will unscrew slightly (to the extent of the clearance at one side of tab 37). Repeated jarring cannot loosen member 28 as it has already been unscrewed the maximum amount permissible by the tab 37 clearances.

It is to be noted that the primer mechanism is constructed for permanent attachment to the breechblock mechanism and obturator. No parts need be detached and be subjected to possible loss or fouling between rounds. The necessity for small tolerances in thread manufacture is alleviated by the use of the present means of joinder between the obturator spindle and the primer mechanism. Direct end thrust and pull on the primer is used in the handling thereof. The pull on the lanyard may be in divers directions and be adequate for firing.

In addition to these advantages, the primer mechanism may be easily disassembled for replacement or repair. The end 104 of rod 180 may be pulled out from bore 106 in the sliding bolt 110 against spring 112 by pulling on the knurled knob 114 and turning the same so that pin 118 will abut the plate 98. The sliding bolt 110 may then be pulled out axially and replaced or repaired, or, if desired, the sleeve 82 with its associated parts may be slipped off the sleeve member 34 without removing the bolt 110.

Having described my invention, what I claim as new and desire to secure by Letters Patent of the United States is:

1. A primer mechanism for ordnance including a cam sleeve member attachable to the rear end of a vented obturator spindle, a slideable bolt mounted within the cam sleeve member carrying primer firing means and a primer rim holder, and a handle protruding through the said sleeve member from said slideable bolt whereby manual move-

11

ment of the handle with respect to the sleeve member may effect a cammed movement of the rim holder toward the vent in the obturator spindle.

2. A primer mechanism and obturator spindle combination for ordnance, said combination including a sleeve member of said primer mechanism having a flange and being keyed to said spindle, a first cylindrical portion threaded to the end of the said spindle with threads of one hand, and a second cylindrical portion threaded to the first cylindrical portion with threads of the opposite hand, the second cylindrical portion bearing against the said flange and holding the spindle and sleeve in abutting relation.

3. A primer mechanism and vented obturator spindle combination for ordnance, said combination including a sleeve member of said primer mechanism having a flange and being keyed to said spindle, means employing said flange for holding the spindle and sleeve member together in abutting relation, and a primer supporting plug extending within said sleeve member and screwed into said spindle against a tight metallic seat and in alignment with the spindle vent.

4. The combination of a primer mechanism and vented obturator spindle, said combination including a flanged sleeve member of said primer mechanism, the end of said sleeve member being locked against the end of the spindle in rigid relation and keyed thereto, the locking means including two coacting coupling members with threads of opposite pitch, the flange of said sleeve member being tightly held between said coupling members, and a primer supporting plug extending from within said sleeve member to a metallic seat within said spindle.

5. A primer mechanism for ordnance including a firing mechanism actuatable by a pull on a longitudinal member extending from within the primer mechanism, the exterior end of said longitudinal member being axially movable within a recess on the primer mechanism, a flared aperture to said recess, a cam knob within said recess having a concave surface contacting the primer mechanism at the flared aperture, a universal connection between the exterior end of the longitudinal member and the cam knob, and means on said cam knob for exerting a pull thereon.

6. A primer mechanism for ordnance including a firing mechanism actuatable by an outward pull on a longitudinal rigid member extending and axially slidably from within the primer mechanism, a cam knob universally linked to said longitudinal rigid member and having a concave side adapted to bear against the flared annular wall of an exterior portion of the primer mechanism for cam action therewith when the cam knob is subjected to a pull in a direction angular to the axis of the longitudinal rigid member.

7. A primer mechanism for ordnance including a sleeve member attachable to the rear end of a vented obturator spindle, a slidable bolt mounted within the sleeve member carrying primer firing means, a handle protruding through the sleeve member from said slidable bolt whereby manual movement of the handle with respect to the sleeve member may effect movement of the slid- able bolt to firing position, and means normally locking said primer firing means relative to said sleeve member but automatically released when said slidable bolt is placed in said firing position.

8. A primer mechanism for ordnance including a cam sleeve member attachable to the end of a vented obturator spindle, an axially slidable bolt

12

mounted within the cam sleeve member and carrying primer firing means together with a primer rim holder, an outer sleeve member axially slid- able on the cam sleeve member and connected to the slidable bolt for movement therewith, an opening through the side wall of the cam sleeve member, a trough-like ejector pivoted to the outer sleeve member and spring-biased to swing through said opening into alignment with the spindle vent when the bolt and outer sleeve member are moved rearwardly, and a cam surface on said cam sleeve member for acting against the ejector to swing it outwardly when the bolt and outer sleeve member are moved forwardly.

15 9. A primer mechanism for ordnance including a cylindrical sleeve member attachable to the end of a vented obturator spindle, an axially slidable bolt mounted within the cylindrical sleeve member and carrying primer firing means, an opening through the side wall of the cylindrical sleeve member, a trough-like ejector pivoted to an outer sleeve longitudinally slidable with said bolt, said ejector being spring-biased to swing through said opening and beyond a position of alignment with the obturator vent for ejecting a spent primer when the outer sleeve is moved rearwardly, and spring means arranged to latch the ejector in said position of alignment when said ejector is manually placed therein.

30 10. The combination of a primer mechanism and a vented obturator spindle, said primer mechanism including a cam sleeve member locked against the end of the spindle in rigid relation and keyed thereto, a primer supporting plug ex- 35 tends from within said cam sleeve member to a metallic seat within said spindle, a slidable bolt mounted within the cam sleeve member carrying primer firing means and a primer rim holder, a handle protruding through the said sleeve mem- 40 ber from said slidable bolt whereby manual move- ment of the handle with respect to the cam sleeve member may effect a cammed movement of the rim holder toward the primer supporting plug, an opening through the side wall of the cam sleeve member, a trough-like ejector pivoted on an outer sleeve member which is rotatable on the cam sleeve member, said ejector being spring- 45 biased to swing through said opening into alignment with the spindle vent when the bolt and handle are moved rearwardly, and a cam surface on said cam sleeve member for acting against the ejector to swing it outwardly when the bolt and handle are moved forwardly.
